UNITED STATES PATENT OFFICE.

CORLIS W. DUGGER, OF VIDALIA, GEORGIA.

HEAT-DISTRIBUTING DEVICE.

Application filed June 20, 1925. Serial No. 38,532.

To all whom it may concern:

Be it known that I, CORLIS W. DUGGER, a citizen of the United States, residing at Vidalia, in the county of Toombs and State 5 of Georgia, have invented certain new and useful Improvements in Heat-Distributing Devices, of which the following is a specification.

This invention relates to a heat distributing device for use in connection with stoves of any type in which the flame strikes the bottom of the cooking utensil, and the invention has for its object to provide, in a manner as hereinafter set forth, a device 10 of the class referred to for distributing the heat of the flame with respect to the bottom of a cooking vessel, so that the bottom thereof will be uniformly heated thereby reducing the scorching or burning of the contents 15 of the vessel to a minimum, as well as preventing the action of the flame from heating one portion of the contents of the vessel at a greater temperature than the other portions thereof to prevent scorching or burning. 20

A further object of the invention is to provide, in a manner as hereinafter set forth, a heat distributing device to cause the contents of a cooking vessel to be heated at an 25 even temperature throughout to reduce scorching or burning of said contents to a minimum.

Further objects of the invention are to provide a heat distributing device in a manner as hereinafter set forth, which is simple 30 in its construction and arrangement, strong, durable, compact, thoroughly efficient and convenient in its use, readily installed and inexpensive to manufacture.

With the foregoing and other objects in view, the invention consists of the novel construction, combination and arrangement of parts as hereinafter more specifically described and illustrated in the accompanying 35 drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a top plan view of a heat distributing device in accordance with this invention, showing the adaptation thereof with respect to a vessel support of the skele-

ton type employed in connection with gas stoves.

Figure 2 is a section on line 2—2, Figure 60 1.

Figure 3 is an edge view of the device.

It is to be understood, that a heat distributing device, in accordance with this invention, can be employed to fit on a vessel support of oil or gas stoves, as well as within the openings in the top of wood and coal stoves or any other types of stoves where the flame strikes the bottom of the cooking utensil. In some instances the term "eye" is employed for that portion of a stove through 65 which passes the flame towards the bottom of the cooking utensil or vessel. The illustration of the device, in connection with the skeleton vessel support or eye of a gas stove is had by way of example so that the position of the device with respect to the eye of 70 a stove can be readily understood.

The vessel support or eye as illustrated comprises a pair of concentric rings 1, 2, which are spaced from each other, as well as being connected together by two sets of radially disposed bars projecting upwardly from the rings 1, 2. The bars of one set are indicated at 3, and the bars of the other set at 4. The bars 3 are of greater length than the bars 4 and are alternately disposed with respect to these latter. The bars 3 and 4 project a substantial distance inwardly from and towards the axis of the ring 1. The cooking utensil, not shown, is mounted on 80 the bars 3, 4 and which space the bottom of the utensil from the top of the rings 1, 2. The ring 1 is of wedge shape in transverse section, as indicated at 5, Figure 2, and the ring 2 is of inverted L shape, as indicated at 85 6, Figure 2, and with the horizontal arm thereof extending towards the ring 1 as well as being spaced a substantial distance therefrom.

A heat distributing device, in accordance 90 with this invention, comprises a circular heat distributing member 7 of any suitable material, preferably sheet metal of the desired gage, and which is slightly concave throughout. The member 7, when arranged in active 95 position, is surrounded and supported from the ring 1. Preferably, the diameter of the member 7 is slightly less than the inner diameter of the ring 1 to provide a passage between said member 7 and the ring 1, as 100 indicated at 8.

The member 7, at the edge thereof, is pro-

vided with a series of radially extending angle-shaped suspension members referred to generally by the reference character 9, and each of said suspension members consists of a vertically disposed arm 10 and a horizontally disposed arm 11 of materially greater length than the height of the arm 10. As shown, the arms 10 are of less height than the height of the ring 1 and when the device is in position said arms 10 are arranged to oppose the upper portion of the inner face of the ring 1. Further, when the device is in position, the arms 11 are seated on the top of the ring 1, extend transversely of said top, project beyond the outer side face of the ring 1 and extend towards the ring 2, but are spaced from the horizontal arms of the latter.

When the device is mounted in position, the member 7 is positioned below the top edge of the ring 1 and it further depends below the bottom edge of said ring. See Figure 2. By setting up the member 7 of concave contour, it provides for the equal distribution of heat throughout the bottom of the cooking utensil. Then furthermore the bottom of such utensil is spaced from the member 7 as well as from the suspension members 9.

The device when set up in the manner as shown in Figures 1 and 2 provides for the equal distribution of heat to all parts of the bottom of the vessel so that one part thereof does not get any hotter than the other, and this provides for the cooking of the contents of the vessel at a uniform temperature throughout and reduces the possibility of scorching or burning of such contents to a minimum, and it is thought that the many advantages of a heat distributing device, in accordance with this invention, can be readily understood, and although the preferred embodiment of the invention is as illustrated and described, yet it is to be understood that changes in the details of construction can be

had which will fall within the scope of the invention as claimed.

What I claim is:—

1. A heat distributing device comprising a concave heat distributing element of circular contour positioned, when active, to depend below a support therefor, and a series of spaced suspension members integral with and extending radially from said element, each of said suspension members including a vertically and a horizontally disposed arm, the vertical arm at its lower end merging into the edge of said element and extending slightly thereabove, the horizontal arm extending outwardly from the upper end of the vertical arm for mounting on a support for said element and of materially greater length than the height of the vertical arm, said element imperforate throughout.

2. In a heat distributing device the combination with a support in the form of an annulus, of a concave heat distributing element arranged within and depending below said annulus, the edges of said element positioned in close proximity to the top of the support and further positioned in close proximity to the inner edge of said annulus, and a series of spaced suspension members integral with and extending radially from said element, each of said suspension members including a vertically and a horizontally disposed arm, said vertical arm merging at its lower end into the edge of said element and of a height to terminate at the top of the support, said horizontal arm extended outwardly from the upper end of the vertical arm and seating on the top of the annulus, said element imperforate throughout and having its portion of greater depth depending below the support.

In testimony whereof, I affix my signature hereto.

CORLIS W. DUGGER.
